GEIGER COUNTER IMPROVEMENT

Allen F. Reid, New York, N. Y., assignor to the
United States of America as represented by the
United States Atomic Energy Commission

Application July 17, 1945, Serial No. 605,543

7 Claims. (Cl. 250—83.6)

1

This invention relates to a Geiger counter and counting method and to an improved gas for the interior of the counter which functions to become ionized and produce an electrical discharge when a high velocity charged particle enters the counter and also to quickly quench the electrical discharge so that the counter may respond accurately to a rapid succession of such particles.

The invention will be described with reference to the drawing in which:

Fig. 1 is a central vertical section of a Geiger counter and a circuit therefor;

Fig. 2 is a top view of the counter;

Fig. 3 is an explanatory curve of an ideal relationship between the number of counts made per minute and the voltage applied to the counter; and

Fig. 4 is a curve of experimental results of the same relationship.

The Geiger counter is an instrument which has been used extensively for measuring the activity of radioactive materials and one construction thereof is illustrated in Fig. 1. The counter comprises a generally bell-shaped glass container 1, a nickel cylinder 2, a tungsten wire 3, and a mica window 4. The container has a flared end 5 and the cylinder similarly has a flared end 6 which fits under the end 5. The wire 3 extends axially within the container and within a glass bore 7. At one end the wire is sealed to the container at a tapered central portion 8; and at the other end the wire is provided with a small ball 9. The cylinder 2 is in contact with a lead 10 which is sealed to the container at a tapered portion 11. The mica window is fused to the flared end 5 of the container. The lead 10 connects the cylinder 2 to the negative pole of a voltage source 12 and the wire 3 is connected to the positive pole. A resistance 13 is connected between the wire and the positive pole of the voltage supply. The counter circuit includes an indicator (not shown) such as an electronic scaling unit and mechanical register for receiving and providing an indication of the electrical impulses produced in said circuit. When, for example, the activity of a radioactive material is to be measured, the material is placed adjacent the thin mica window 4.

In order to more clearly understand the invention, an explanation of the operation of the counter is necessary. In general, the operation of the counter involves the ionization of the gas within the counter by the advent of a high velocity charged particle and the causation of an electrical discharge. For example, in counting beta-

2

rays emitted by a radioactive material, when a beta-ray enters the counter it collides with molecules of the gas present and in so doing detaches electrons from atoms of the gas molecules, or in other words ionizes the molecules. These detached electrons, in a high field, may in turn collide with other gas molecules and detach more electrons. The result of this chain-like sequence of events is to produce a large number of electrons which surge to the positively charged wire 3 and are discharged there, this event being indicated by the indicator.

It is very important that the counter be promptly restored to its initial condition in order to ensure that the next succeeding beta-ray, which may enter the counter in the next fraction of a second, will be counted. In other words, it is necessary that the electron discharge which is initiated by the entry of a beta-ray in the counter shall be promptly extinguished or quenched.

Quenching of the discharge may be accomplished by various methods. By one method an extinguishing circuit is used which causes a drop in the high positive potential of the wire sufficient to quickly extinguish the discharge. By another method, which has the advantage of simplicity, the gas itself present in the counter in conjunction with the resistance 13 in the counter circuit, has the property of quickly extinguishing the discharge.

The manner in which the quenching gas operates to extinguish the discharge may be as follows. When a beta-ray enters the Geiger counter it detaches electrons from the gas molecules and these electrons are attracted to the positively charged wire 3 where they are discharged, thereby decreasing the positive potential of the wire. The gas molecules which have had an electron removed are positively charged ions and hence are attracted to the cylinder 2 which comprises the negative electrode. Since these positive ions are relatively slow moving owing to their large mass, they are not immediately discharged at the negative electrode but form a layer or sheath of positively charged particles between the wire 3 and the cylinder 2. A point is reached in this process where the difference of potential between the positively charged wire and the sheath of positive ions is so small that electrons will not be pulled across to the wire 3 fast enough to cause sufficient secondary ionization for a continuous discharge. At this point the electron discharge ceases and the wire is thereby restored to its original high positive potential so that the cycle

described above is capable of repetition on the entry of the next beta-ray into the counter.

The beta-rays emitted by the radioactive material are particles whose energies are spread over a wide range. The higher the energy of the particle, the less voltage needed to start the discharge. Fig. 3 shows an ideal relationship between the number of counts per minute observed and the applied voltage. Referring to Fig. 3, at very low voltages applied to the counter, the field is too low to initiate the discharge. As the applied voltage is increased, beta-rays of relatively high energy, representing a proportion of those which enter the counter, cause discharges. As the voltage is further increased, the field becomes strong enough to count not only the high energy beta-rays but some of the lower energy ones and a range on the voltage axis is finally reached, seen as a plateau on the curve, at which a number of counts per minute is observed which amounts to 100 per cent of the beta-rays entering the effective part of the counter. Above this plateau the curve rises indicating that some of the beta-rays are counted twice or three times. On further increasing the voltage there is finally a continuous discharge owing to the fact that the applied voltage is so high that the potential difference between the wire and the sheath of ions is great enough to attract the electrons to the wire at a speed to cause sufficient secondary ionization to create a continuous discharge.

In the ideal curve of Fig. 3 the point at which 100 per cent of the beta-rays which enter the counter are counted will coincide with the plateau of the curve. In other words, this point on the count axis will be maintained over a range of applied voltages. The necessity for this is apparent when it is considered that even with a good voltage regulator there will always be some variation in the voltage applied to the counter. Therefore the curve should have a plateau which has an extent at least sufficient to include the anticipated variations in voltage. The voltage range which should be included in the plateau will therefore depend on the precision of the voltage regulator used, or on the variation of the supply if no regulator is used. For example, a good voltage regulator will be accurate to within $\frac{1}{2}$ of 1 per cent. If it is desired to apply 1400 volts there will then be a possible variation of 7 volts either way. The plateau should therefore include this range.

The ideal plateau of Fig. 3 is perfectly horizontal, that is, the count is 100 per cent along the entire plateau. Hitherto it has been found experimentally that the plateau actually has a slope which may be as much as 2 per cent of the counts per 100 volts. It is apparent that when the applied voltage varies slightly and the percentage of beta-rays counted varies with the applied voltage, it is not possible to maintain the counter at a voltage at which 100 per cent of the beta-rays are counted, this being the objective for accurate results. Thus, any slope of the plateau away from the perfectly horizontal will introduce an error which it is desirable to keep to a minimum.

It may be shown that the characteristics of the curve depend upon the nature of the quenching gas. Although all gases form ions when electrons are detached from atoms of the gas molecules, not all gases, when ionized, will form a sheath of ions which will effectively quench the discharge. In some gases there will be a second-

ary discharge of electrons sufficient to start the discharge again. This may be due to the fact that the positive ions recombine with electrons at the negative electrode to form a combination which is unstable and from which electrons again are split off to start the discharge anew. Double pulses and triple pulses or a continuous discharge may result from this incomplete quenching. Also, gases of different chemical composition vary in the quantum of energy which is needed to ionize them. Some will be ionized only by beta-rays of relatively high energy and others by beta-rays of relatively low energy. If the voltage applied to the counter is made high enough even those gases which require high energy beta-rays to ionize them may be ionized by beta-rays of lower energy, but at the high voltages required only a continuous discharge in the counter will be obtained. It is thus apparent that the nature of the gas in the counter determines the nature of the curve obtained expressing the relationship between the percentage of beta-rays counted to the applied voltage, and that a desirable gas is one which will permit the attainment of a curve closely approximating the ideal, that is, a curve with a wide and horizontal plateau.

Preferably the gas should have a number of other characteristics which are quite important. The gas should not be poisonous so that it may be handled without special precautions. This is an objection to the use of lead tetra-methyl which has previously been used as gas for the counter. The gas should also not be sensitive to light inasmuch as the effect of light on a light-sensitive gas is to cause independent discharges so that a spurious count is registered. Therefore, when the gas is light-sensitive the counter must be carefully shielded from light. This may be disadvantageous when the object whose radioactivity is to be measured is very large or, as frequently happens, if a part of the human body is to be measured, since then the part to be measured must be placed outside the shield with the result that some of the radioactivity does not get through the shield. Lead tetramethyl and also an argon-ethyl alcohol mixture which is a commonly used gas are both objectionable because of their light-sensitivity.

The gas should be one which is not quickly decomposed under the conditions existing in the Geiger counter. When an electron is split off from an atom of a gas molecule the bond between the deprived atom and the rest of the molecule is weakened. If this bond is weakened sufficiently the atom will split off from the molecule, i. e. the gas molecule will be chemically decomposed. It is desirable that this chemical decomposition of the gas molecule should take place at a very slow rate so that the tube may be used over a long period of time without the necessity of refilling. In other words, the molecule must be of such a nature that an electron may be split off from one of the atoms under the conditions at which the counter will be operated but this process should not result in rapid chemical decomposition of the gas. Furthermore, the decomposition products of the gas should not interfere with the proper functioning of the counter.

It is apparent, therefore, that a desirable gas for a Geiger counter must combine a large number of diverse characteristics in order to function in the required manner.

An object of the invention is therefore to pro-

vide a Geiger counter filled with an improved quenching gas.

Another object of the invention is to provide a quenching gas which will permit the attainment of a curve expressing the relationship between the number of counts per minute and the applied voltage, in which there is a wide and horizontal plateau.

A further object of the invention is to provide a quenching gas which may be used without any special precautions and over a long period of time with good results.

According to the invention, the alkyl mono-halides of two to six carbon atoms in their vapor phase have been found to be excellent quenching gases for Geiger counters.

The alkyl halide used may have any of the possible isomeric forms such as, for example, the normal, the iso-, the secondary, or the tertiary form.

The halogen atom of the halide may be chlorine, bromine, iodine or fluorine, but only one halogen atom should be present in the molecule.

The halide may be an ethyl, propyl, butyl, amyl, or hexyl halide.

It has also been found that among the alkyl mono-halides of two to six carbon atoms, there are individuals or groups of individuals which are particularly desirable with respect to a certain characteristic. For example, it has been found that the mono-halides of higher chain length give better plateaus so that if an especially good plateau is desired for a measurement, one of the amyl halides or hexyl halides should be used. Also, as the atomic weight of the halogen atom decreases, the stability of the molecule increases and hence its lifetime increases. Thus a fluoride has greater stability and a longer life than a chloride. A quenching gas which combines a number of desirable properties is, for example, n-amyl fluoride.

The pressure of the gas in the counter will be adjusted with reference to the voltage one wishes to apply to the counter. For a given pressure, the plateau of one gas will occur at a different voltage range from that of another gas. However, the plateau of a gas may be shifted to a higher voltage range by increasing the pressure of the gas. Thus if one desires to operate at higher voltages, the pressure of the gas used is adjusted accordingly. At higher voltages better plateaus are obtained. For the mono-alkyl halides of two to six carbon atoms a useful range of pressures was 9 to 225 mm. of mercury.

Fig. 4 is a curve of experimental results obtained when the counter of Fig. 1 was filled with n-amyl chloride vapor to a pressure of 20 mm. of mercury. It is seen that the curve is similar to the ideal curve of Fig. 3. The plateau has a range of 1500-1560 volts which is a satisfactory

voltage variation tolerance. The slope of the plateau did not exceed $\frac{1}{2}$ of 1 percent per 100 volts as compared with 2 percent per 100 volts which is the best slope normally obtained with an argon-ethyl alcohol mixture. After one million counts the counter operated with the same accuracy. The gas was non-poisonous and was unaffected by light.

Although the invention has been described with particular reference to the measurement of beta-rays by a Geiger counter, it is apparent that it is equally applicable for the measurement of other high velocity charged particles such as positrons and secondary electrons. It will be apparent to those skilled in the art that a Geiger counter may be operated in the proportional region which covers a comparatively lower voltage range and that the quenching gases of the present invention may be used for such application.

Since many embodiments might be made of the present invention and since many changes might be made in the embodiment described, it is to be understood that the foregoing description is to be interpreted as illustrative only and not in a limiting sense.

I claim:

1. A Geiger counter including a quenching gas comprising an alkyl mono-halide of two to six carbon atoms.
2. A Geiger counter including a quenching gas comprising a hexyl mono-halide.
3. A Geiger counter including a quenching gas comprising an amyl mono-halide.
4. A Geiger counter including a quenching gas comprising n-amyl chloride.
5. A Geiger counter including a quenching gas comprising n-amyl fluoride.
6. A Geiger counter including a quenching gas comprising a mono-alkyl halide of two to six carbon atoms at a pressure of 9 to 25 mm. of mercury.
7. A Geiger counter including a quenching gas comprising n-amyl chloride at a pressure of 20 mm. of mercury.
